LAMP SHADE BRACKET

Lauritz W. Andersen, Waterbury, Conn.

Application March 30, 1932. Serial No. 601,962

6 Claims. (Cl. 240—138)

This invention relates to electric light fixtures, and more particularly to a bracket for detachably supporting a bridge lamp shade upon an electric light bulb.

5 One object of this invention is to provide a shade bracket of the above nature comprising a threaded screw shell adapted to fit the conventional central screw socket of a bridge lamp shade, and also having a pair of depending split wire 10 clips for snap-engagement upon an upstanding lamp bulb.

A further object of this invention is to provide a bracket of the above nature adapted to convert a conventional bridge lamp shade into a table 15 lamp shade.

A further object is to provide a lamp shade bracket of this nature which will be simple in construction, inexpensive to manufacture, easy to install and manipulate, compact, ornamental 20 in appearance, and very efficient and durable in use.

With these and other objects in view there has been illustrated on the accompanying drawing, one form in which the invention may be conveniently embodied in practice.

In the drawing:

Fig. 1 represents a front view of the lamp shade bracket as it appears when in position upon a light bulb and supporting a lamp shade, shown 30 in dotted lines.

Fig. 2 is an end view of the bracket.

Fig. 3 is a top plan view of the same.

Fig. 4 is an enlarged cross sectional view of the 35 same, taken along the line 4—4 of Fig. 3, looking in the direction of the arrows.

Referring now to the drawing in which like reference numerals denote corresponding parts throughout the several views, the numeral 10 indicates a bracket member, preferably stamped 40 from sheet brass and having an upper closed threaded shell 11 adapted to be screwed into a socket 12 of a bridge lamp shade 13, which is indicated by dotted lines in Fig. 1. The top of the shell 11 has an upwardly concave dome 14 which serves to enhance the strength and ornamental appearance of the device.

In order to attach the bracket member 10 to an upstanding electric light bulb 15 of conventional form, said bracket 10 is provided with a pair of wire members 16 and 17, terminating in two pairs of opposed semi-circular loops 18 and 19 adapted to snap over the lamp bulb 15. The members 16 and 17 are permanently secured to the shell 11 by means of a pair of semi-circular horizontal loops 20 and 21 connecting the vertical

loops 18 and 19, and rigidly held in position by means of a pair of outwardly bent semi-circular flanged beads 22 and 23 tightly crimped around the exterior of said wire loops 20 and 21, as best shown in Figs. 3 and 4.

Operation

In operation the shell 11 will first be screwed into the socket of the bridge lamp shade 13, and the depending wire loops 18 and 19 then snapped over the electric light bulb 15 (see Fig. 1).

One advantage of the present invention is that the lamp shade may be tilted to any desired angle upon the bulb, and will be retained in position by reason of the gripping action of the resilient loops 18 and 19 thereupon. While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric lamp shade bracket, a cup-shaped screw shell fitting within the screw socket of a bridge lamp shade, a pair of depending split-wire clips for snap engagement upon an electric light bulb, and means for rigidly securing said clips to said shell.

2. In an electric lamp shade bracket, a cup-shaped screw shell fitting within the screw socket of a bridge lamp shade, a pair of depending split-wire clips for snap engagement upon an electric light bulb, and means for rigidly securing said clips to said shell, said means consisting of rolled beads on said shell encasing the upper sections of said clips.

3. In an electric lamp shade bracket, a threaded cup-shaped shell for engaging the screw socket of a bridge lamp shade, said shell having a pair of depending resilient wire clips, each of said clips comprising a pair of parallel lamp engaging semi-circular loops and an upper horizontal semi-circular loop connecting said depending loops, said shell having means for embracing said upper loops to hold said clips rigidly in position.

4. In an electric lamp shade bracket, a threaded cup-shaped shell adapted to be screwed into the screw socket of a bridge lamp shade, said shell

having two pairs of depending outwardly convex clip members for embracing an electric light bulb.

5. In an electric lamp shade bracket, a threaded cup-shaped shell open at the bottom adapted to be screwed into the screw socket of a bridge lamp shade, said shell having two pairs of depending outwardly convex clip members for embracing an electric light bulb.

10

6. In an electric lamp shade bracket, a cup-shaped screw shell adapted to fit within the screw socket of a bridge lamp shade, a pair of depending split-wire clips for snap engagement upon an electric light bulb, and a pair of upwardly and inwardly rolled beaded flanges on the base of said shell for rigidly securing said clips to said shell.
